UNITED STATES PATENT OFFICE

FRANK W. MILLER, OF CHICAGO, ILLINOIS, ASSIGNOR TO FRANCLARE COMPANY, OF CHICAGO, ILLINOIS, A CORPORATION OF ILLINOIS

BOILER BLOW-OFF AND REFILLING SYSTEM

Application filed May 5, 1923. Serial No. 636,835.

This invention pertains generally to boiler washing and refilling systems, and has more particular reference to improvements for conserving heat units and increasing the efficiency of such a system.

One of the primary features of this invention resides in the provision of improved means for condensing the blow-off steam and also the exhaust steam from the pumps and 10 other steam operated apparatus in the power plant, which condensed steam and the heat units contained therein are delivered to the refill water tank for boiler refilling purposes.

Another feature of this invention is the 15 provision in a system of the above type of means for condensing the steam which is blown off, by water from the refilling tank thereby maintaining the temperature of the refilling water as high as possible.

20 A still further feature of this invention is the provision in connection with the system of the above type of means for automatically admitting condensing water to the condenser when steam to be condensed is blown into such condenser.

For the purpose of facilitating an understanding of my invention, I have illustrated on the accompanying drawing a preferred embodiment thereof, the single figure of the 30 drawing being a fragmentary elevation of so much of a boiler washing and refilling system as is necessary for an understanding of my invention.

Referring to the drawing more in detail, 35 reference characters 5, 6, and 7 indicate, respectively, a refill drop, a blow-off drop, and a washout drop, adjacent one of the pits in a roundhouse. The washout drop 7 is connected with the washout line 8, which receives the washout water at suitable temperature from a washout tank (not shown), the washout circulating line 9 being connected to return washout water from the end of the washout line to the tank for the purpose of 40 maintaining a circulation in the line.

The blow-off drop 6 is connected with the blow-off line 11, which has interposed therein a separator 10 of well known or preferred construction adapted to separate the blow-off 45 steam and water, and from which the blow-

off water is delivered into the washout tank through pipe 20, and the blow-off steam is conducted through the continuation 12 of the blow-off line to a T 13 connected with a pipe 14 extending below the water level in 55 the refill tank 15, and with a pipe 16 adapted to discharge into the condenser 17. This condenser may be of any preferred construction, preferably of the injector type, and the discharge pipe 18 therefrom is also adapted 60 to deliver into the tank 15.

The refill water is withdrawn from the tank 15 for refilling purposes through the pipe 30 by the refill pump 19, from which it is delivered through the pipe 21 into the refill line 22, extending into the roundhouse, and to which the refill drop 5 is connected. A refill circulating line 23 is connected at one end with the end of the refill line, and at its other end is adapted to deliver through a 70 nozzle 24 into the condenser 17. The refill pump is adapted to operate continuously at slow speed to maintain a circulation in the refill line, the refilling water being returned through the circulating line 23 into the condenser, where it commingles with the blow-off steam delivered by the pipe 16, serving 75 thereby to condense this steam, and being then returned with the condensed steam to the refill tank. 80

Since the limited amount of water returned by the relatively small circulating pipe 23 is ordinarily insufficient to condense any considerable proportion of the blow-off steam delivered during a blowing off operation, I 85 have provided means for delivering additional water to the condenser, as will now be described.

A pipe 25 connected to the refill line by means of a T 26 is connected also at 27 90 with the refill circulating line, and since this line between the connection 27 and the nozzle is preferably of larger capacity than the main portion of the refill circulating line, water in considerable quantities may be delivered directly from the pump 19 into the condenser. For the purpose of automatically shutting off the pipe 25, when no blowing-off operation is being performed, I have 95 interposed in the pipe 25 a control valve 28 100.

adapted to be automatically actuated by a thermostatic device 29 interposed in the blow-off line 12. When no blow-off steam is passing through the blow-off line, this element 5 will close the valve 28, shutting off direct flow of water from the pump to the condenser, but when a blowing-off operation is being performed, the temperature of the blow-off steam will actuate the thermostatic 10 element 29 to thereby open the valve 28 and permit the delivery of auxiliary water direct from the pump into the condenser for condensing purposes.

The water in the tank 15 is replenished by 15 delivering cold, fresh water thereto, and this water is also utilized for condensing the steam delivered to the tank. A water supply line 31 is accordingly connected to the condenser 17, the pipe preferably entering the 20 side thereof, and delivery of water through this pipe is regulated by a valve 32, automatically controlled by a maximum water level float 33. Whenever the liquid level in the tank 15 falls below this maximum level, the 25 valve 32 is opened to deliver water to the tank. This water may be delivered either into the condenser 17, as explained, or if the shut-off valve 34 interposed in the pipe 31 be closed, the water is then delivered through 30 a branch 35 into a second condenser 36, which discharges through a pipe 37 into the tank. Steam is delivered to this secondary condenser from a pipe 38, which extends into the power house and receives the exhaust 35 from the various steam employing units therein, including the refill pump 19 from which exhaust steam is delivered into the line 38 through a pipe 39. Live steam for operating the pump is supplied thereto from 40 any suitable source through a steam supply pipe 41.

If the refilling demands upon the tank 15 should be greater than the replenishment of the tank through the pipe 31, the water level 45 therein will fall until a minimum desirable water level is reached, whereupon a minimum level float 42 will open a valve 43 in the auxiliary water supply pipe 44, permitting the delivery of additional water to replenish the tank. The pipe 44 discharges, as will be 50 apparent, laterally into the condenser 36 so that this water also is utilized for condensing the exhaust steam.

It will be apparent, therefore, that the 55 blow-off steam from the locomotives, and the exhaust steam from the units in the power house, is all conserved and delivered to the refill tank. All of the water also which is delivered to this tank for replenishing purposes, is discharged either into the blow-off steam condenser 17, or the exhaust steam condenser 36 to condense the steam, thereby preventing waste by loss of steam escaping from the tank. The blow-off steam is 60 condensed by cold water delivered from the 65

pipe 31, also by return refill water delivered by the refill circulating line 23, and this water is supplemented by refill water delivered through the pipe 25 under control of the thermostatically actuated valve 28. The 70 exhaust steam is condensed in the condenser 36 by water from the pipes 31 and 35 whenever the water level in the tank is below the maximum controlled by the float 33, and such additional water as is delivered through the 75 pipe 44 under control of the minimum level float 42 is also discharged into the condenser 36 for condensing purposes.

Various modifications of the specific arrangement disclosed may obviously be resorted to, without departing from the essence of the invention, as defined in the following claims.

I claim:

1. In a boiler blow-off and refilling system, the combination of a refill water tank, a blow-off steam line, adapted to deliver into said tank, a condenser interposed in said line, a refill line connected to said tank, a circulating line connected at one end with the refill line and at its other end with said condenser, a branch line leading from the refill line to the condenser, a valve in said branch line, means adapted to be actuated by the steam in the blow-off line for controlling said valve for regulating the flow of refill water through said branch line to the condenser.

2. In a boiler blow-off and refilling system, the combination of a refill water tank, a blow-off steam line connected to said tank, a condenser interposed in said line, an exhaust steam line connected to said tank, a second condenser interposed in said exhaust steam line, a circulating line connected to deliver circulating water to said first condenser, thermostatically controlled means for delivering refill water to said first condenser, and means controlled by the water level in the tank for delivering cold water to both of said condensers.

3. In a boiler blow-off and refilling system, the combination of a refill water tank and a refill line connected thereto, a blow-off line, a condenser connected with said blow-off line and discharging into said tank, a circulating pipe from said refill line to said condenser, an exhaust steam line connected with the tank, a second condenser interposed in said exhaust steam line, a cold water pipe connected with said first condenser, means controlled by the water level in said tank for admitting cold water through said pipe to said first condenser, and independent means controlled by the water level in the tank for admitting cold water to said second condenser.

4. In a boiler blow-off and refilling system, the combination of a refill water tank, a condenser, a pump and a refill main connected

to said tank, a blow-off steam line connected to said condenser, a replenishing water pipe connected to the condenser, means controlled by the water level in the tank for regulating the delivery of replenishing water through said pipe into the condenser, a return circulating line connected with said main and said condenser for circulating water through said main back into the tank, and thermostatically controlled means for delivering additional water from the refill tank to said condenser.

5 5. In a boiler blow-off and refilling system, the combination of a refill water tank, a blow-off steam line, an exhaust steam line, condensers connected to said lines, respectively, a discharge connection from each condenser to said tank, means for delivering replenishing water to the blow-off line condenser, means for delivering return circulating refill water to the blow-off line condenser, means for delivering refill water to said blow-off line condenser, means controlled by the maximum water level in the refill tank for regulating the delivery of replenishing water to the blow-off line condenser, means controlled by the steam in said steam line for regulating the delivery of said refill water to said condenser, means controlled by the maximum water level in said tank for regulating 25 the delivery of replenishing water to the exhaust line condenser and means controlled by the minimum level of said tank for regulating the delivery of replenishing water to said exhaust line condenser.

30 6. In a boiler blow-off and refilling system, the combination of a refill water tank and a refill line connected thereto, a blow-off line, a separator in said line for separating the blow-off steam and water, a pipe for conducting said blow-off steam from the separator to the tank, a condenser connected with said pipe and said tank, a connection from said refill line to said condenser, thermostatic means for controlling the flow of refill water from said line to said condenser, a circulating line for returning refill water from the end of the refill line to the condenser, an exhaust steam line connected with the tank, a second condenser interposed in said exhaust steam line, means controlled by the maximum water level in the tank for delivering cold water to both of said condensers, and means controlled by the minimum water level in the tank for delivering cold water to the second of said condensers only.

35 7. In a system of the class described, the combination of a boiler blow-off line, a boiler refill line, a boiler refill tank, a condenser communicating with said tank and adapted to condense the blown-off steam and to discharge into said tank, both of said lines communicating with said condenser and adapted to discharge thereto, means for withdrawing refill water from said tank and discharging said water into said refill line, and means in

said refill line controlled by the flow of steam in said blow-off line for governing the discharge of said refill line to said condenser.

8. In a system of the class described, the combination of a boiler blow-off line, a boiler refill line, a boiler refill tank, a condenser communicating with said tank and adapted to condense the blown-off steam and to discharge into said tank, a normally closed connection between said refill and said condenser, said blow-off line communicating with said condenser and adapted to discharge thereto, means in said blow-off line operatively connected to said connection for opening the same when steam is flowing in said blow-off line, and means for withdrawing water from said tank and discharging said water into said refill line.

9. In a boiler blow-off and refilling system, the combination of a refill water tank, a blow-off steam line, a condenser in said line discharging into said tank, a refill main, a pump connected to said tank and main for pumping refill water through the main to points of use for refilling, and a pipe connected to said pump and condenser for conducting heated water directly from the tank under thermostatic control of said blow-off steam into said condenser for further heating by the steam from said blow-off line.

10. In a boiler blow-off and refilling system, the combination of a refill water tank, a blow-off steam line, a condenser in said line discharging into said tank, a refill main, a pump connected to said tank and main, a pipe connected with the discharge of the pump and with said condenser and having a valve interposed therein, and thermostatic means for regulating said valve connected to said steam line actuated by the flow of steam to said condenser.

11. In a boiler blow-off and refilling system, the combination of a refill water tank, a blow-off steam line, a condenser in said line discharging into said tank, a refill main, a pump connected to said tank and said main for pumping heated refill water from the tank through said main to points of use for refilling, means for returning part of the water being pumped from the tank directly back to said tank through said condenser without causing it to flow through said main, and thermostatically controlled means connected to said steam line and the first said means adapted for regulating the flow of water through the first said means in accordance with the flow of steam in said blow-off line.

12. In a system of the class described, blow-off, wash-out and refill lines, a separator in the blow-off line, a line for steam separated by the separator, a refill tank connected with the refill line, a condenser discharging into said tank and connected with the refill and separated steam lines, thermostatic means in the separated steam line for controlling the

- delivery of refill water to the condenser, cold water pipes connected with said condenser and said tank, means controlled by one water level in the tank for regulating the delivery of cold water to said condenser, and means controlled by another water level in said tank for regulating the delivery of cold water directly into said tank.
13. The method of blowing down and refilling a locomotive comprising blowing off the steam and water, separating said steam and water, discharging said steam through a condenser into a refill tank, condensing said steam by injecting into said condenser heated water pumped from the refill tank, and regulating said injection of refill water in accordance with a characteristic of said separated steam.
14. The method of blowing down and refilling a locomotive comprising blowing off the steam and water, separating said steam and water, discharging said steam through a condenser into a refill tank, condensing said steam by injecting into said condenser heated water pumped from the refill tank, regulating said injection of refill water in accordance with a characteristic of said separated steam, and injecting cold water into the condenser when the water lowers to one level in the tank, and adding cold water directly to the tank when the water therein lowers to another level.
15. The method of blowing down and refilling locomotives comprising blowing off the steam and water from the locomotives simultaneously, separating said steam from said water, discharging the separated steam through a condenser into a refill storage tank and as said steam flows into said condenser causing it to mix therein with previously heated water pumped directly from the refill tank into said condenser under thermostatic control of said separated steam to be returned therefrom back to the refill tank.
16. The method of blowing down and refilling locomotives comprising blowing off the steam and water, separating said steam and water, discharging the separated steam into a condenser, maintaining a body of heated water in a refill storage tank, and circulating from the tank into said condenser and back again into said tank a stream of the stored water whenever blown off separated steam is flowing into said condenser.
17. The method of blowing down and refilling locomotives comprising blowing off the steam and water from the locomotives, separating said steam and water, discharging the separated steam into a condenser, maintaining a body of heated water in a refill storage tank and circulating streams of water therefrom into said condenser and back again into said tank whenever blown off separated steam is being discharged into the condenser, refilling the locomotives from said refill tank,
